UNITED STATES PATENT OFFICE.

SAMUEL S. HAWKINS, OF JACKSONVILLE, ALABAMA.

AUTOMATICALLY-RELEASABLE SKID CHOCK.

Application filed December 18, 1924. Serial No. 756,792.

To all whom it may concern:

Be it known that I, SAMUEL S. HAWKINS, a citizen of the United States, residing at Jacksonville, in the county of Calhoun and State of Alabama, have invented certain new and useful Improvements in Automatically-Releaseable Skid Chocks, of which the following is a specification, reference being had to the accompanying drawings.

10 This invention relates to aeroplanes, and the general object of the invention is to provide a device which will impede the forward movement of an aeroplane when it is starting until the propellers have reached a determined speed, the device then being automatically tripped, as it were, and the machine then going forward and rising.

It is necessary in starting that an aeroplane should take a relatively long run over the ground before it can get up speed enough to rise, and the object of the present invention is to provide a device which will impede the forward movement of the plane until the propellers have reached a speed which will be sufficient to cause the machine to lift almost immediately, thus doing away with the long starting run and permitting the machine to rise in a short space and over relatively rough ground or in fields where there is high grass or something of this character which will impede the forward movement of the plane.

A further object is to provide a device of this character which is so constructed that it may be adjusted so that it will automatically trip when the speed of the propellers reaches any desired point and thus so that the machine will not trip until the propeller reaches a speed of twenty, thirty or forty miles an hour more or less, and which will trip automatically so that the aviator will not have to trip the device himself.

A still further object is to provide a device of this character which will, to a certain extent, act to kick the machine off the ground or lift it as the machine starts.

My invention is illustrated in the accompanying drawing, wherein:

Figure 1 is a fragmentary elevation of the forward end of an aeroplane showing the landing gear thereof and my invention applied thereto;

Figure 2 is a front view of the construction shown in Figure 1;

Figure 3 is a fragmentary elevation show-

ing the manner in which the machine moves forward and trips the chock;

Figure 4 is a fragmentary side elevation showing a modification, the device being in its holding position;

Figure 5 is a like view to Figure 4 but showing the device in its released position;

Referring to this drawing, and particularly to Figure 1, it will be seen that I have illustrated so much of an ordinary aeroplane as is necessary to disclose my invention. In the drawing, 10 designates the bottom of the fuselage of the aeroplane, 11 and 12 the upper and lower planes, 13 the landing wheels, 14 the usual struts supporting the landing wheels, and 15 the axle of the landing wheels. Disposed on each side of the landing gear are the bars 17, each of which is formed upon its upper face with a series of recesses 18 adapted to receive the axle 15. These bars 17 are connected at their forward ends by means of a transverse bar 19 which is angularly bent at its extremities and pivotally or otherwise engaged with the bars 17. These bars 17 are preferably formed at their forward extremities with sharp-pointed, relatively wide shoes 20, the points of which are adapted to engage the ground and the shoes being relatively wide so that these extremities of the bars 17 will not mire down. Preferably the bars 17 are also formed with spurs 21 disposed at a slight angle to the bars 17 and adapted to engage the ground. This is necessary because when in actual use the bars 17 are disposed at an acute angle to the ground.

Pivotally connected to the rear ends of the bars 17 are the links 22, which at their upper ends are pivotally connected at 23 to links 24, which in turn extend rearward and are pivoted upon pins 25 or like elements projecting out from the floor of the fuselage. The bars 22 are preferably connected by means of a transverse bar 26, whose extremities are angularly bent. Connected to the bar 26 is a spring 27 which extends forward and is in turn connected to any suitable supporting member as, for instance, the vertical member 28 projecting up through the bottom of the fuselage. The rear ends of the bars 24 project below the bottom of the fuselage and are connected by resilient means 29 which will resist upward movement by bearing against the bottom of the fuselage so that as the forward ends of the bars 24 are

shifted downward, this spring bearing against the bottom of the fuselage will yieldingly resist this downward movement of the forward ends of the bars. The whole purpose of the springs 27 and 29 is to yieldingly resist the downward movement of the supporting members 24.

In practice, before the aeroplane starts off, the bars 17 are brought forward to the position shown in Figure 1 and the axle 14 is engaged in any one of the notches 18. If it is engaged in the notch *a*, the aeroplane will be impeded in its forward movement until a relatively low rate of speed has been secured by the propellers. If it is placed in the notch *b* a higher rate of speed will be necessary before the detainer will trip, as before stated, and a still higher rate of speed will have to be developed in order for the device to be tripped if the axle is disposed in the notches *c*. When the bars 17 are disposed forward and downward, as before described, the pointed extremities 20 and 21 of the bars will engage with the ground. The propeller is then started and in order for the machine to move forward it will have to lift the bars 17 to a nearly vertical position so that the propeller must have developed a certain rate of speed before there will be sufficient force to urge the machine forward against the impediment afforded by the bars 17 and the cross bar 19. When this speed has been developed, the member 17 will move into nearly a vertical position, and the front wheels of the landing gear will jump the obstruction, as it might be termed, and the machine will be lifted partly into the air and will start to fly after a relatively short run, the length of this run being less, of course, if a higher speed has been developed before the machine can start, and longer if a lower speed has been developed. As the machine jumps forward under the impetus of the propeller, the bars 17 will turn from their forwardly and downwardly inclined position to a downwardly and rearwardly inclined position or that shown in Figure 3 and, of course, form no impediment to the movement of the wheels in any way and the machine then proceeds as usual. Preferably the recesses 18 are formed with relatively contracted throats so as to form seats within which the axles 15 will rest, these recesses being thus formed so as to prevent the movement of the axle out of the recesses without causing the lifting up of the chocks or bars 17 and the consequent lifting up of the machine and its landing gear.

In Figures 4 and 5 I show another form 60 of the device which is simpler than that shown in Figure 1 but which operates on the same general principle. The same reference numerals have been used for the parts of the fuselage, landing wheels and struts. In this form there is mounted upon the axle of

the landing wheels and exterior to each landing wheel a link 30 which is pivoted upon the axle. The free end of this link is pivotally connected by a bolt 31 to the bar 32 which at its lower end is pointed, as at 33. 70 These bars 32 are the equivalent of the bars 17 previously described and may be formed in any suitable manner and constitute chocks. Each bar or chock 32 is formed with a plurality of openings 34 through 75 which the bolt 31 may pass, these openings being arranged in longitudinal series. Each bar or chock 32 is formed with an ear 35 and this ear carries a pin 36 to which a spring 37 is connected, this spring extending 80 upward to the fuselage and being connected to the fuselage in any suitable manner.

In the use of this device, the bolts 31 are adjusted in the proper holes 34 to suit the speed at which it is desired to start the aeroplane. The forward ends of the chocks 32 are forced into the ground and impede the forward movement of the aeroplane, the springs 37 acting, as shown in Figure 4, to hold these chocks forced into the ground. 90 When the speed of the aeroplane has increased the proper amount it will move forward and be simultaneously lifted in order to pass over the chocks, the chocks turning to the position shown in full lines in Figure 95 5 and eventually to the position shown in dotted lines in Figure 5, when they are fully dropped.

It will be seen that the construction shown in Figures 4 and 5 operates in practically 100 the same manner as the construction shown in Figures 1 and 2, and that when the machine has secured sufficient impetus it will be forced forward, the bars or chocks 32 fulcruming on the ground, and the landing gear will be lifted up precisely in the same manner as heretofore described until the wheels have vaulted over the obstruction, as it were. The adjustment of the device to control the machine at different speeds is secured by adjusting the bars or chocks 36 longitudinally with reference to the link 30, and it is obvious that when the bolts 34 are disposed in the rearmost pair of holes in the bars 32 that the bars will be projected to the 110 greatest extent and a greater speed will have to be secured before the machine can possibly overleap this obstruction and pass onward and that when the bolts 31 are disposed in the lowest holes 34 a less speed will 115 have to be secured.

Obviously many minor modifications might be made without departing from the spirit of the invention.

I claim:—

1. The combination with an aeroplane having a propeller and including a transverse rod, of means for detaining the machine until the propeller has reached a predetermined speed including a pair of ground- 13

engaging bars mounted one on each side of the machine and normally extending downward and forward into engagement with the ground, each of said bars having a notch in 5 which said transverse member engages, and means pivotally supporting said bars upon the fuselage of the machine.

2. The combination with an aeroplane having a propeller, of means carried thereby 10 and in an operative position preventing forward movement of the propeller under a speed less than a predetermined speed but shifted into inoperative position when the propeller has reached said predetermined 15 speed, said means being adjustable to cause the tripping of the means at any one of a number of predetermined speeds.

3. The combination with an aeroplane having a landing gear and a propeller, the landing gear including a transversely extending axle, of ground-engaging bars pivotally supported at their upper ends upon the aeroplane and when in operation extending 25 downward and forward and intersecting the axle, the ground-engaging bars having each a plurality of notches to receive the axle and being transversely connected and said bars having a length from their pivotal axes to the ground-engaging ends of the bars 30 greater than the distance from said pivotal axis vertically downward to the ground, and springs acting to lift the bars into a rearwardly extending position when the speed of the propeller has forced the axle of the 35 running gear out of said notches.

4. The combination with an aeroplane having a landing gear and a propeller, the landing gear having a transversely extending member, of means for detaining the machine until the propeller has reached a predetermined speed including a pair of ground-engaging bars mounted one on each side of the machine and normally extending downward and forward into engagement with the ground and operatively supported for pivotal movement from a downwardly and forwardly inclined position rearward and upward in a vertical plane, springs urging the forward ends of said bars downward and 45 rearward, and means for supporting the transversely extending member of the landing gear upon said bars until said bars have been turned into a rearward position. 50

ing gear on said bars until the said bars are in their rearwardly directed position.

5. The combination with an aeroplane having a landing gear and a propeller, the landing gear having a transversely extending member, of means for detaining the machine until the propeller has reached a predetermined speed including a pair of ground-engaging bars mounted one on each side of the 60 machine and normally extending downward and forward into engagement with the ground and operatively supported for pivotal movement from a downwardly and forwardly inclined position rearward and upward in a vertical plane, springs urging the forward ends of said bars downward and 65 rearward, and links pivotally connected to the projecting members and pivotally connected each to one of said bars whereby to support the transversely extending member of the landing gear upon said bars until said bars have been turned into a rearward position.

6. The combination with an aeroplane having a landing gear and a propeller, the landing gear having a transversely extending member, of means for detaining the machine until the propeller has reached a predetermined speed including a pair of ground-engaging bars mounted one on each side of the machine and normally extending downward and forward into engagement with the ground and operatively supported for pivotal movement from a downwardly and forwardly inclined position rearward and upward in a vertical plane, springs urging the forward ends of said bars downward and 70 rearward, and links pivotally connected to the projecting members and pivotally connected each to one of said bars, each of said bars having a plurality of longitudinally extending openings, and a bolt disposable in any one of said openings and pivotally connecting the bar to said link whereby to support 75 the transversely extending member of the landing gear upon said bars until said bars have been turned into a rearward position.

In testimony whereof I hereunto affix my signature.

SAMUEL S. HAWKINS.
